CLAIM

The ornamental design for an internal combustion engine, as shown.

DESCRIPTION

FIG. 1 is a front elevational view of an internal combustion engine showing our new design;
FIG. 2 is a rear elevational view thereof;
FIG. 3 is a right side elevational view thereof;
FIG. 4 is a left side elevational view thereof;
FIG. 5 is a top plan view thereof;
FIG. 6 is a bottom plan view thereof, and
FIG. 7 is a right side perspective view thereof.

FIG. 1

FIG. 2

FIG. 3

FIG. 4

FIG. 5

FIG. 6

FIG. 7
